UNITED STATES PATENT OFFICE.

HARRY LUTHER BEACH, OF COSHOCTON, OHIO.

DESIGN FOR A BRUSH-HOLDER.

No. 38,220.

Specification for Design.

Patented Sept. 4, 1906.

Application filed February 15, 1906. Serial No. 301,312. Term of patent 14 years.

To all whom it may concern:

Be it known that I, HARRY LUTHER BEACH, a citizen of the United States, residing at Coshocton, in the county of Coshocton and State of Ohio, have invented a new, original, and ornamental Design for a Brush-Holder, of which the following is a specification.

In said drawing the figure is a perspective view showing the front side of the new design.

I claim—

The ornamental design for a brush-holder as shown.

HARRY LUTHER BEACH.
